MICROPHONE BOOM

William A. Mueller, Hollywood, Calif., assignor
to United Research Corporation, Burbank,
Calif., a corporation of Delaware

Refiled for abandoned application Serial No.
639,321, October 24, 1935. This application
October 17, 1936, Serial No. 106,157

5 Claims. (Cl. 179—152)

This invention relates to acoustic cinematographic apparatus and more particularly to a novel means for rotating a microphone suspended from a microphone boom during the taking of 5 sound motion pictures.

It has been a common practice in the photographing of motion pictures with a sound accompaniment, to suspend the microphone above the actors so that the desired dialogue will be recorded thereby. This apparatus often took the form of a long pole with a hook at the end thereof and from which a microphone was suspended. This was carried from place to place as desired by the continuity of action in the plot, always 10 keeping the microphone above and in front of the actor speaking and out of range of the camera.

This method suffered from many defects as will be readily understood, in that it was difficult 20 to turn the microphone quickly so that it would always be presented directly towards the actor who was speaking.

This fault and other defects are overcome by the present invention, an object of which is to 25 rotate a microphone from a remote point so that it may be quickly orientated in a desired direction during sound recording.

This is accomplished by rotatably mounting a microphone on a boom, means being provided 30 for rotating the microphone from a remote point. Preferably the rotatable microphone is provided with a resilient mounting whereby all extraneous vibrations are eliminated.

Further details of this invention will be apparent from the following description when read in conjunction with the accompanying drawing, 35 wherein:

Fig. 1 is a side elevation of a movable microphone boom employing the device of this invention.

Fig. 2 is a diagrammatic view showing a preferred means of remote control for the microphone supporting frame.

It has been found by experiment that the most 40 advantageous position for the recording microphone, when recording sound motion pictures, is pointing directly down at a speaker from an angle of about 45°. This is easy to accomplish when there is only one speaker, but when there 45 are a plurality of speakers, the microphone must be turned quickly from one to the other in order to follow the conversation. The present invention accomplishes this by providing the following apparatus: A skeleton frame truck 1, supported 50 for mobility by suitable dirigible wheels such as

2 and 3. An upright supporting column 4 is carried on truck 1 and mounted for rotary movement in a large roller bearing 5. Suitable struts 6 and 7 are provided for the sake of rigidity. A cross-arm 8 is pivotally mounted at the top of column 4. Arm 8 pivots about a point 9 offset from the center of column 4 by means of an offset bracket 10 fastened to the top of column 4. At one end of cross-arm 8 there is a counterweight 11. The other end thereof has a depending 10 bracket 12 which supports a raw hide friction wheel 13 journaled to rotate about a point 14. A second cross-arm 15 telescopes arm 8 at the point 12 and rests on the wheel 13. The arm 15 reciprocates in the arm 8 and is actuated by 15 means of a pair of spaced pulleys 16 and 17 mounted adjacent either end of arm 8. One end of a wire cable 18 is tied to the inner end (not shown) of telescoping arm 15. It passes over pulley 16, around a pulley 19, journaled to rotate 20 about the point 9 and over a drum 20 mounted for free rotation, to an intermediate point on column 4. The other end of cable 18 is tied to the inner end (not shown) of telescoping arm 15, passes over the spaced pulley 17, around pulley 25 19 and over drum 20. Drum 20 is provided with a suitable handle 21 so that when the handle 21 is turned, the arm 15 is made to reciprocate in the arm 8 at will.

Attached to the outer end of arm 15 is a 30 rotatable circular clamp 22, having a locking wing nut 23. Depending from clamp 22 is a small shaft or spindle 24, to the end of which is journaled a horizontal pulley 25. A twin-armed cradle 26 is mounted on pulley 25. Cradle 26 has a series of 35 hooks 27, 28, 29 and 30 mounted on the inside of the arms thereof and a pair of lugs 31 and 32, one mounted on the outside of each of the arms of the cradle 26.

The microphone assembly consists of a small 40 cylindrical amplifier 33 with a semi-circular carrying ring 34, mounted on the top thereof. A second semi-circular supporting ring 35 is mounted at the lower end of amplifier 33 in order to accommodate the microphone 36. Microphone 45 36 can be tilted as desired by means of two locking studs 37 and 38 at the horizontal diameter of the ring 35.

The microphone assembly is resiliently mounted in the frame 26 by means of a pair of rubber 50 bands or other elastic members 39 and 40 which extend through the carrying ring 34 and over the hooks 27 and 28 respectively. A second pair of rubber bands 41 and 42 surround the amplifier 33 at a mid-point and hook over the members 55

29 and 30 respectively. A single rubber band 43 is stretched between the studs 31 and 32 and supports the amplifier 33 on either side.

The cradle 26 (Fig. 2) is rotated by remote control means consisting of a handle 44 fastened to a pulley 45 which is journaled to an intermediate point at the side of column 4. An endless cable 46 passes around the annulus of pulley 45 and over a double pulley 47 that is suspended 10 from the cross-arm 8. A loop is then formed in the cable 46 when it passes over a second double pulley 48 similarly supported. A weight 49 fastened to a double pulley 50 rides in the loop so formed between pulleys 47 and 48 and imparts 15 tension to the cable 46. Cable 46 then passes through a pair of spaced guide bearings 51, depending from the cross-arm 8 and finally around the annulus of pulley 25. Thus when the handle 44 is raised or lowered, the cradle 26 is rotated 20 at will.

An electric cable 52, which supplies current to the microphone assembly, is fastened to the end of telescoping arm 15. It then passes over a pair of spaced pulleys 53 and 54 suspended from the 25 cross-arm 8 and forms a loop between pulley 54 and a similar spaced pulley 55. A balance weight 56, fastened to a pulley 57, rides in the loop thus formed between the pulleys 54 and 55, and imparts tension to the cable 52. The end of cable 30 52 is fastened to a suitable electric plug 58 conveniently mounted on the column 4.

The microphone is raised or lowered, and the cross-arms 8 and 15 are tilted by means of a lever arm 59, journaled at one end to a fixed pin 60 35 mounted on the cross-arm 8 adjacent the counter-weight 11. The other end of lever 59 is journaled to a locking pin 61 mounted at an intermediate point on an arm 62. Arm 62 is rotatably fastened to the post 4 at a point 65. An arcuate plate 63 having a series of spaced holes 64, serves as a 40 convenient means of adjustment for the position of locking pin 61 so that when the pin 61 is moved, the cross-arms 8 and 15 are raised or lowered as desired.

In the operation of this device, the microphone 45 36 is set at the desired angle of tilt by means of the studs 37 and 38. It is then raised to the desired height by means of raising or lowering the arm 62. The microphone is swung over the set and out of range of the camera, by means 50 of turning handle 21 which reciprocates arm 15 as described. The action then begins and as the actors talk or turn, the microphone is presented directly to them by either raising or lowering the handle 44, which turns the microphone from one to the other at will.

This application is a refile for abandoned application S. N. 639,321, filed October 24, 1935, which became abandoned on July 21, 1936.

Having thus described the invention what is claimed as new and desired to be secured by Letters Patent is:

1. A microphone boom comprising a truck, a support carried thereby, a telescoping cross-arm carried by said support, a microphone carried by said cross-arm, a plurality of adjacent hand-operated devices mounted on said support, means connected to one of said hand-operated devices

for telescoping said cross-arm to move said microphone into positions at different distances from said support, and an extensible, mechanical cable mechanism connected to another of said hand-operated devices and to said microphone and adapted to be extended and retracted for rotating said microphone when moved different distances away from said support. 5

2. A microphone boom comprising a truck, a support carried thereby, a cross-arm on said support, a spindle carried by said cross-arm, a pulley on said spindle, a cradle connected to said pulley, a microphone, means for resiliently supporting said microphone on said cradle, a hand-operated device mounted on said support and a cable having a weighted loop connecting said hand-operated device to said pulley, whereby said hand-operated device is adapted to rotate said microphone, and means for varying the distance between said microphone and said support whereby 20 said microphone may be rotated by said hand-operated device when moved into positions at different distances from said support. 10

3. A microphone boom comprising a truck, a support carried thereby, a telescoping cross-arm 25 carried by said support, a microphone carried by said cross-arm, a plurality of adjacent hand-operated devices mounted on said support, means connected to one of said hand-operated devices for telescoping said cross-arm to move said 30 microphone into positions at different distances from said support, and a self-adjusting extensible, mechanical mechanism connected to another of said hand-operated devices and to said microphone and adapted to be extended and retracted for rotating said microphone when moved different distances away from said support. 35

4. A microphone boom comprising a truck, a support carried thereby, a cross-arm on said support, a spindle carried by said cross-arm, a pulley 40 on said spindle, a cradle connected to said pulley, a microphone, means for resiliently supporting said microphone on said cradle, a hand-operated device mounted on said support and flexible means having a weighted loop connecting said 45 hand-operated device to said pulley, whereby said hand-operated device is adapted to rotate said microphone, and means for varying the distances between said microphone and said support whereby said microphone may be rotated by said hand-operated device when moved into positions at different distances from said support. 50

5. A microphone boom comprising a truck, a support carried thereby, a telescoping cross-arm carried by said support, a microphone carried by 55 said cross-arm, a plurality of adjacent hand-operated devices mounted on said support, means connected to one of said hand-operated devices for telescoping said cross-arm to move said microphone into positions at different distances from said support, and a self-adjusting flexible mechanical mechanism connected to another of said hand-operated devices and to said microphone and adapted to be extended and retracted for rotating said microphone when moved different distances away from said support. 60
